CLOSURE OPERATOR

Percy M. Griffin, Albany, N. Y., assignor to Consolidated Car-Heating Company, Inc., Albany, N. Y., a corporation of New York

Application September 21, 1943, Serial No. 503,302

4 Claims. (Cl. 121—44)

1

My invention relates to fluid actuated closure operators and particularly to hydraulically actuated operators for opening and closing car doors, bus doors and the like.

For many years brakes on commercial passenger carrying vehicles have been actuated by compressed air and, probably, because a supply of compressed air must be available for the operation of such brakes, the door opening and closing devices have been operated by compressed air from the same source. Such devices operate at relatively low air pressure, say around 100 pounds per square inch, and, because considerable power must be developed the air actuated operators have been comparatively large.

With the increasing use of hydraulic brakes and the like which require a source of supply of liquid, usually oil, under high pressure, it has become desirable to provide an hydraulically actuated door operator which may draw its power from the same source as the hydraulic brake actuating mechanism, and thus avoid the necessity of providing both a source of compressed air and a source of liquid under high pressure. Furthermore, it is desirable, in many instances, to provide safety devices which prevent the doors of a passenger vehicle from being opened when the vehicle is in motion with the brakes off and the problem is considerably simplified where both doors and brakes are actuated by the same medium. By utilizing high pressure, say of the order of two thousand pounds per square inch, a great deal of power can be generated by comparatively small mechanisms with parts moving through comparatively short distances and thus the size of the closure operators may be substantially reduced. However, due to the high pressures involved the present designs of air actuated closure operators are not at all suited for hydraulic operation because of the special problems encountered in the change over involving leakages of liquid under such high pressures through gaskets and the like and the extremely close tolerances to which reciprocating pistons and the like must be fitted to provide positive operation. Aside from the fact that leakages result in substantial loss of pressure, efficiency and positiveness of operation, they are particularly objectionable in door operators since such devices are ordinarily positioned over the doors operated thereby and through which passengers enter and leave the vehicle.

The general object of my invention is to provide an hydraulically actuated closure operator of simple design in which pressure leaks are sub-

2

stantially eliminated and which is so designed that substantial leakage past the pistons and otherwise can be eliminated without the necessity of having the pistons, cylinders and other parts fitted to such extremely close tolerances that they are unduly expensive to produce. Another object is to provide an hydraulically actuated closure operator of the differential pressure reciprocating type in which the cylinders are separate units so that in case of defects which develop either during the fabrication of the cylinders or during the operation thereof it is not necessary to discard both cylinders to remedy a defect in one. Another object is to provide a novel unitary means in such a device for regulating the rate of closure opening, closing, or both, which will be free from the usual fine adjustments, provide a fixed rate of operation throughout indefinitely long periods without servicing, and which is quickly interchangeable with a similar unit to provide substantially any other operating rate that may be desired. A further object is to provide a device of this character which is easy to manufacture, assemble, test and service.

With these objects in view my invention includes the novel elements and the combinations and arrangements thereof described below and illustrated in the accompanying drawings in which—

30 Fig. 1 is a small scale plan view of my closure operator showing the control valve and fragmentary portions of the pipe system associated therewith;

35 Fig. 2 is a sectional plan view taken in a horizontal plane through the common axis of the cylinders;

Fig. 3 is a fragmentary plan view of the larger cylinder;

40 Fig. 4 is a fragmentary plan view of the smaller cylinder;

Fig. 5 is an end view of a split bushing;

Fig. 6 is a section of a plug adapted to be threaded into the end of the smaller cylinder;

Fig. 7 is a fragmentary top view of my closure operator; and

Fig. 8 is a section of Fig. 7 in the plane 8—8.

Referring to the drawings and particularly to Figs. 2, 7 and 8 my device comprises a central element or block 1 through which extend the bolts 3 and 4 serving to secure the device to a suitable foundation 5 (see Fig. 8). The central element 1 is provided with a vertical bore 6 adapted to receive the bushings 7 and 8 which form bearings for the vertical shaft 9 with which the pinion 10 may be integral or to which it may

be keyed. The bushing 7 is pressed tightly into the bore 6 while the bushing 8 is pressed lightly into the bore and prevented from turning therein by means of the dowel 11. The bottom of the bore is sealed with a cap 12. Between the pinion and the bushings 7 and 8, which are preferably the "Oilite" type, are steel thrust washers 13 and 14. The bushings and shaft assembly are held in place by means of the cover plate or cap 15 which is secured to the top of the central element by means of screws 16. To disassemble this part of the device it is necessary only to remove the cap 15 and pull the shaft 9 with the bushing 8, the thrust washer 14 and the pinion 10 thereon out of the element.

The central element 1 is also provided with a horizontal bore 17 which intersects the bore 6 and which is adapted to form a bearing for the reciprocating rack 18. The rack teeth engage the teeth of the pinion and thus the rack is prevented from turning in the bore 17. The central element 1 is also provided with an oil drain 19 which is drilled from the outside of the central element to intersect the bore 6. In order to facilitate connecting pipes to carry the drainage in either direction from the closure operator a cross-drain 20 is drilled to intersect the drain 19. After the drains are drilled the outside end of the drain 19 is plugged, as shown at 21 (see Fig. 8).

From the foregoing it will be apparent that axial movement of the rack 18 will cause the pinion 10 to rotate in one direction or the other and thus turn the shaft 9.

In order to reciprocate the rack I provide two separate cylinders with pistons therein, one on each side of the central element 1. Referring particularly to Fig. 2, the cylinder 22 is a unitary, cup-like casting provided with the flanges 23 and 24 which abut the central member 1 and which are secured thereto by means of the cap screws 25 and 26. The end of the cylinder 22 which is adjacent the central element 1 is bored out to receive the steel washer 27 and counterbored to receive the "neoprene" washer 28. Adjacent its open end the cylinder 22 is also bored out to receive the gland element 29 and the packing 30. The gland element 29 abuts the washer 27 which in turn abuts the "neoprene" washer 28 which lies in contact with the side of the central element 1 and serves both as a gasket and also as a cushioning element for the adjacent piston as will be hereinafter explained. The length of the gland element 29 and the thickness of the packing, and the washers 27 and 28 are such that, when the cap screws 25 and 26 are tightened the packing 30 and the "neoprene" washer are firmly compressed; the packing forming a close engagement with the hollow piston 31 and the "neoprene" gasket forming a tight seal between the end of the cylinder and the central element. The head 32 of the cylinder is provided with a threaded opening 33 adapted to receive the pipe-threaded portion 34 of a valve element 35 which will be hereinafter described.

Secured to the opposite side of the central element by means of cap screws 44 and 45 is a second cylinder 36 which is an integral casting and provided in the head with a threaded opening 37 adapted to receive the pipe-threaded plug 38 (see Fig. 6). This cylinder is of smaller diameter than the cylinder 22 and has a piston 39 mounted to reciprocate therein. The packing 40, the gland 41, a steel washer 42 and a "neoprene" washer or gasket 43 are associated with the cylinder 36.

in the same manner as the like parts in the cylinder 22.

As illustrated the heads of the pistons 31 and 39 contact the ends of the rack 18 and thus may reciprocate the rack and turn the pinion 10.

The valve element 35, a unitary, plug-like structure, which is threaded into the head of the large cylinder 22 constitutes a means for automatically checking the rate of movement of the piston 31 as it approaches the end of its fluid exhausting stroke. It comprises the pipe-threaded portion 34 and a tubular portion 46 which extends into cylinder 22 and also a substantial distance into the hollow, cup-like piston 31. The valve element 35 is provided with a female pipe-thread 47 adapted to form a high pressure tight joint with a pipe 48 (see Fig. 1) through which liquid is conveyed to the interior of the cylinder 22. The interior of the tubular portion 46 of the valve element 35 communicates directly with the pipe 48 through the small passage 49 and also with the interior of the cylinder 22 through the openings 50 and 51. The interior of the cylinder also communicates with the passage 49 through the very small passage 52.

Slidably mounted to reciprocate within the tubular portion 46 is a needle-valve element 53 adapted to seat in and close the passage 49. The element 53 is normally urged away from its seat by means of a comparatively light, helical spring 54. The inner end of the tubular portion 46 is partially closed by the split bushing 56 (see Figs. 2 and 5) and the stem of the plunger 51 is mounted to reciprocate in this bushing. Between the head 58 of the plunger and the adjacent end of the needle-valve element is a comparatively stiff, helical spring 59. Normally, neither the spring 54 nor the spring 59 is compressed, but both of them may be compressed to yieldingly force the needle-valve element into its seat by the contact of the inside of the head of the piston 31 with the stem of plunger 51 as it moves to the left on its fluid-exhausting stroke.

In order to bleed the cylinders 22 and 36, respectively, I provide each of them on the top and near the head thereof with small openings which are normally sealed by means of the plugs 60 and 61, respectively (see Figs. 3 and 4).

Referring particularly to Figs. 1 and 2 it is to be understood that the pipe 62 connects at all times with an accumulator (not shown) containing the operating liquid under high pressure, say around 2000 pounds per square inch, while the pipe 63 connects at all times with the sump of the accumulator from which the liquid is pumped into the accumulator. 64 is a three-way valve which, in one position, will permit liquid to flow therethrough from the pipe 62 through the pipe 65 into pipe 48 and thus into the larger cylinder. When the valve is in this position pipe 63 is shut off at the valve. In the other position of the valve 64, the flow of liquid from pipe 65 is cut off at the valve and communication is provided between pipes 48 and 63 so that fluid in the larger cylinder 22 may be discharged therefrom through the pipes 48 and 63 into the sump.

It will be apparent from the foregoing that, since the diameter of piston 31 exceeds the diameter of piston 39, when valve 64 is positioned to admit fluid to cylinder 22, although the pressure per square inch of piston area is identical in both cylinders, nevertheless piston 31 will be moved toward the smaller cylinder 36, and fluid in cylinder 36 will be forced out of the cylinder through the plug 38 and into the pipe 62. When the valve

64 is positioned to cut off communication between pipes 48 and 65 and provide communication between pipes 48 and 63 the constant pressure on the head of piston 39 will force it towards cylinder 22 and fluid will be discharged or exhausted from cylinder 22 through the passages 49 and 52 into pipe 48.

Referring particularly to Figs. 1 and 2, if it be assumed that the closure operator is being used to open and close the doors of a bus or car and that the doors are closed, piston 39 will be as far to the right as it can be moved. That is to say the right hand end of the piston 31 will be near or in contact with the washer 27, the rack 18 will have moved as far to the right as possible, and cylinder 22 will be in communication with the accumulator through the passages 52 and 49, pipe 48, valve 64 and pipe 65. To open the doors valve 64 is merely turned to such a position as will exhaust fluid from cylinder 22 which will cause piston 39 to force piston 31 and rack 18 to the left until the head of piston 39 contacts washer 42. Then, to close the doors, valve 64 is merely turned to the position where communication between pipes 48 and 65 is established and communication cut off between pipes 48 and 63.

On the opening movement, when piston 39 is being forced to the left, cylinder 22 initially discharges into the sump through both openings 49 and 52. However, as piston 31 moves to the left the head thereof will contact the stem of the plunger 57 and force it to the left. The movement of the plunger 57 to the left will force the needle-valve 53 into its seat against the compression of the light spring 54 and, thereafter, as the plunger 57 is moved further to the left, spring 59 will be compressed. When the needle-valve 53 is in its seat the rate of discharge of fluid from cylinder 22 will be substantially reduced because it can then be discharged only through the small passage 52. Thus, the rate of movement of the piston 31 will be correspondingly reduced so that, just before the door is fully opened, its rate of movement will be substantially checked and slamming open of the doors will be prevented.

The sizes of the passages 49 and 52 depend on the pressure of the liquid in the accumulator, the difference in cross-sectional area between the piston 31 and the piston 39, and the time interval within which it is desired to open and close the door. Ordinarily a vehicle door should open in about one and one-half second and completely close in about two to two and one-half second. However, with my device substantially any rates of opening and closing can be provided by selecting a plug 38 and a valve element 35 having fluid passages therethrough of the appropriate size. It will be noted that there are no adjustments of any kind to be made in order to effect and maintain any opening and closing rates that may be desired. The manufacturer may carry in stock plugs such as 38, and valve elements such as 35, having various combinations of passages therethrough and thus provide a closure operator having any desirable rate of opening and closing; it being necessary only to fit the operator with the proper size plug and valve element. It should also be noted that my device differs materially from those checking devices in which the cross-sectional area of the outflow passage is positively controlled by an element cooperating directly with the piston, as illustrated in U. S. Letters Patent No. 2,114,334, granted to Conklin on April 19, 1938. In such devices it is obvious that, since the passage is positively closed or reduced in area by the movement

of the piston, it cannot be restored to its normal full-flow area until the piston has moved some distance in the reverse direction, and since the rate of piston movement in the reverse direction depends upon the rate at which the actuating fluid can enter the cylinder, the reverse movement of the piston, in its initial stage, is retarded to the same degree that its direct movement is checked in the final stage thereof. In my device, pressure of the entering fluid in passage 49 will immediately force the needle valve 53 into open position and thus at once provide a passage of full-flow area for the inflowing fluid.

The difficulty in maintaining free from leaks a device of this character which operates under extremely high pressure is recognized and the device has been designed with this difficulty in mind. It is possible by means of pipe-threaded joints to produce perfectly tight connections but it is almost impossible to do this by designs involving the use of gaskets which are prone to leak or even to blow out under high pressure. It will be noted that in my design pressure leaks are eliminated by reason of the fact that the pressure ends of the cylinder have only pipe-threaded connections. As illustrated, the cylinders are closed by pipe-threaded plugs, which are preferred to caps, but pipe-threaded caps engaging the outer ends of the cylinders might be employed. The "neoprene" gaskets 28 and 43 are not subjected to liquid pressure, and any liquid which leaks past the piston will be drained off to the sump of the accumulator through the drains 19 and 20.

Furthermore it will be noted that, because the cylinders in my design are separate units any leak or defect which develops in either one of them can be readily corrected merely by removing that cylinder alone and replacing it with a new one. It is apparent also that, if desired, a valve element such as that shown at 35, may be used in the smaller cylinder where it is desired to check the closing movement of the door or, in both cylinders where it is desired to check both the opening and closing movements thereof. Thus, I have provided a closure operator of extremely simple design which is adapted to operate under very high liquid pressures and which can be readily serviced and maintained in perfect operating condition.

While I have described my invention in its preferred embodiment it is to be understood that the words which I have used are words of description rather than of limitation and that changes within the purview of the appended claims may be made without departing from the true scope and spirit of my invention.

What I claim is:

1. In a fluid actuated closure operator of the differential pressure type including a cylinder having a piston mounted for reciprocation therein, a unitary valve for reducing the rate of fluid discharge from said cylinder as said piston approaches the end of its fluid-exhausting stroke comprising an elongated element having a tubular portion and provided with means adapting it to be fixedly secured to said cylinder with said tubular portion extending therein and also with passage means for the flow of fluid therethrough to and from said cylinder, means slidably mounted in said tubular portion for reducing the effective cross-sectional area of said passage means and means, including resilient means, separate from said area-reducing means adapted to cooperate with said piston and with said area-reducing means for actuating the latter as said piston approaches the end of its fluid-exhausting stroke.

2. In a fluid actuated closure operator of the differential pressure type including a cylinder having a piston mounted for reciprocation therein, a unitary valve for reducing the rate of fluid discharge from said cylinder as said piston approaches the end of its fluid-exhausting stroke comprising an elongated element having a tubular portion and provided with means adapting it to be fixedly secured to said cylinder with said tubular portion extending therein and also with passage means for the flow of fluid therethrough to and from said cylinder, means slidably mounted in said tubular portion for reducing the effective cross-sectional area of said passage means and means, including resilient means, mounted in said tubular portion and slidably therein independently of said area-reducing means adapted to cooperate with said piston and with said area-reducing means for actuating the latter as said piston approaches the end of its fluid-exhausting stroke.

3. In a fluid actuated closure operator of the differential pressure type including a cylinder having a piston mounted for reciprocation therein, a unitary valve for reducing the rate of fluid discharge from said cylinder as said piston approaches the end of its fluid-exhausting stroke comprising an elongated tubular element provided with means for securing it in said cylinder and with at least two passages for the flow of fluid therethrough to and from said cylinder, a movable passage closing element adapted to close one of said passages, means normally urging said closing element to passage-open position, means adapted to cooperate with said piston for moving said closing element into passage-closed position as said piston approaches the end of its fluid-exhausting stroke, and yielding means positioned between and cooperating with both said closing element and said piston cooperating means.

4. In a hydraulically actuated motor of the differential pressure type including a cylinder having a piston mounted for reciprocation therein, a device for reducing the rate of fluid discharge from said cylinder as said piston approaches the

end of its fluid-exhausting stroke without materially restricting the inflow of fluid to said cylinder at the commencement of its fluid-intaking stroke, said device comprising a unitary, plug-like structure having a threaded portion adapting it to be secured in a threaded opening in said cylinder and having passage means therein for the flow of fluid to and from said cylinder, a valve element having a seat in said passage means and adapted, when seated, to reduce the effective fluid flow capacity of said passage means without entirely closing the same, and means independent of said valve element but cooperating therewith and with said piston for effecting a seating of said valve element as said piston approaches the end of its fluid-exhausting stroke; said last mentioned means including means adapted to yield under pressure of fluid entering said passage means to effect an unseating of said valve element and restore said passage means to its full flow capacity irrespective of the position of said piston.
